UNITED STATES PATENT OFFICE.

FRED W. COOPER AND ALBERT R. EVERED, OF ROCHESTER, NEW YORK.

MOTOR-CYCLE STAND.

1,123,490.

Specification of Letters Patent.

Patented Jan. 5, 1915.

Application filed November 19, 1913. Serial No. 801,767.

To all whom it may concern:

Be it known that we, FRED W. COOPER and ALBERT R. EVERED, of Rochester, in the county of Monroe and State of New York, have invented certain new and useful Improvements in Motor-Cycle Stands; and we do hereby declare the following to be a full, clear, and exact description of the same, reference being had to the accompanying drawings, forming a part of this specification, and to the reference-numerals marked thereon.

Our invention relates to motor cycle stands, of the type which is pivotally arranged upon the frame of the machine, and adapted when in operation to lift the frame so as to raise the rear wheel clear of the ground, the stand being moved upwardly out of the way when the machine is moving, and it has for its primary object to improve the construction of such devices so as to afford a simple but effective arrangement of parts which will operate automatically to return the stand to its normal or inoperative position when not in use.

A further object of the invention is to provide a mechanism that is positive in its operation, returning the stand to its upper position instantly when it is relieved from the weight of the machine, and entirely obviates the possibility of its being dislodged and dropping while the machine is moving.

To these and other ends the invention consists in certain improvements and combinations of parts all as will be hereinafter more fully described, the novel features being pointed out in the claims at the end of the specification.

In the drawings: Figure 1 is a view in side elevation of a motor cycle equipped with one embodiment of the invention, and showing the stand in operative position, the rear part of the machine being lifted clear of the ground; Fig. 2 is a similar view with parts broken away, the stand being raised to its inoperative position; Fig. 3 is an enlarged sectional view taken on the line 3^a—3^a of Fig. 2, and Fig. 4 is a sectional view on the line 4^a—4^a of Fig. 2.

Similar reference characters throughout the several views indicate the same parts.

The invention is applicable to any form of bicycle, although it is more especially designed for use in connection with motor driven machines of the general type shown in the drawings, and in which—

1 designates the rear part of the frame,

while 2 is the supporting stand pivoted to the frame at 3 and provided with an arm 4 for engagement with the frame when the stand is lowered as shown in Fig. 1.

5 5 is a spring catch mounted on the guard 6 and adapted to engage the stand and hold it in its upper position as shown in Fig. 2.

The difficulty heretofore with devices for this purpose has been that if the stand is released accidentally from the catch 5, it drops into engagement with the ground while the machine is in operation, sometimes causing considerable trouble. Some forms of spring returning devices have been proposed for 70 effecting movement of the stand to its inoperative position and for retaining it there, but these have been more or less inefficient, and lacking in positiveness of operation, and further they have not been sufficiently strong 75 to stand the strain to which they are subjected. To overcome these various objections, we have provided a rigid actuating member connected to the stand and so mounted upon the frame that when the stand is relieved from the weight of the machine, it is forced instantly to its upper or inoperative position and held there with sufficient pressure to overcome any accidental jar to which it may be subjected. This result is 80 obtained by means of a pair of relatively movable members with means for forcing them apart, one of said members being attached to the frame and the other to the stand. In the present embodiment, the rigid 85 actuating device consists of the rod 7 connected to the supporting stand by means of the bifurcated coupling 8, and carrying at its opposite end an adjustable piston or collar 9. The latter is movable within the 90 casing or cylinder 10 which carries a removable cover 11 at one end, and is pivotally attached at its opposite end to a bracket 12. The bracket 12 is adjustably secured to the frame, and may be attached 95 to any convenient point, depending upon the size of the machine and the other requirements. 13 is a spring, housed within the casing 10 and arranged between the collar or piston 9 and the opposite end of the 100 casing, so that when the stand is in its vertical position as shown in Fig. 1, the spring 13 is compressed, and as soon as the machine is moved forwardly far enough to relieve the stand, the spring 13 is free to 105 act, and expanding, throws the stand quickly up into engagement with the catch 110

1 designates the rear part of the frame,

5. The strength of the spring 13 is sufficient, with the arrangement of the parts set forth, to effect an instantaneous return of the supporting stand to its inoperative position, and to hold it rigidly in such position while the machine is moving, and while we have shown the catch 5 for engaging the supporting stand, this is not absolutely essential, as the latter will be held 10 upwardly by the actuating device with sufficient pressure to withstand any accidental displacement.

We claim as our invention:

1. In a motor cycle, the combination with 15 a frame, of a stand pivoted to the frame; a casing pivotally mounted on the frame, a piston movable in said casing and having

connection with the stand, and a spring housed in said casing and engaging the aforementioned piston.

2. In a motor cycle, the combination with a frame, of a stand pivoted at the rear part thereof, a casing and piston movable relatively to each other, one being connected to the stand and the other pivotally mounted on the frame at a point forwardly of the stand, and a spring housed in said casing and coöperating with the piston.

FRED W. COOPER.

ALBERT R. EVERED.
